D12-203.

OR D 13,424 EX

NO. 13,424

Nov 14, 1882

UNITED STATES PATENT OFFICE.

JOHN L. POPE, OF CLEVELAND, OHIO.

DESIGN FOR A CARRIAGE-STEP.

SPECIFICATION forming part of Design No. 13,424, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for Carriage-Steps, of which the following is a specification, reference being had to the accompanying photographic illustration, forming part thereof.

My invention relates to a new design for carriage-steps; and it consists particularly in ornamenting the plate with a central figure substantially square in outline, that is connected to and included within a large polygonal figure, that in turn is connected at various points to the inner edge of the rim of the plate of the step.

In the photograph forming part of this specification the ornamentation, it will be observed, is made of raised bars or webs that form in the center of the plate what may be called a "square figure," having a V-shaped notch, *a*, in each side, and having each of the corners united by a short piece, *b*, to the polygonal figure *c*, that surrounds said square-like figure, *25* and which is connected to the inner edges of

the border-like part *e* at the points *d*. The many-angled figure *c* is also connected to the border of the plate or step by the Y-shaped portions *h*. The corners of the plate are rounded, and at each corner it will be seen *30* that the space included between the two forks of the Y-shaped part *h* is filled up or closed, as may be done, too, with various other openings shown in the design without loss of the effect in general seen in the accompanying *35* photographic illustration.

What I claim as new, and desire to secure by Letters Patent, is—

A design for a carriage-step, having a central figure, substantially such as shown, with *40* in and connecting with the polygonal figure *c*, the whole surrounded by the border *e*, substantially as shown and described.

In witness whereof I have hereunto set my hand this 31st day of May, 1882.

JOHN L. POPE.

In presence of—

A. A. POPE,
C. M. COPP.
